United States Patent Office.

MATTHEW D. GRAY, OF TERRE HAUTE, INDIANA.

Letters Patent No. 98,952, dated January 18, 1870.

IMPROVEMENT IN WATER-ELEVATORS.

The Schedule referred to in these Letters Patent and making part of the same.

To all whom it may concern:

Be it known that I, MATTHEW D. GRAY, of Terre Haute, in the county of Vigo, and State of Indiana, have invented a new and improved mode of Elevating Water from Wells; and I do hereby declare that the following is a full and exact description thereof, reference being had to the accompanying drawings, and to the letters of reference marked thereon.

The design is calculated for the elevating of water from wells by crank, without turning the same backward to let the bucket down in the well.

Upon the frame-work, marked A A in the drawings, are marked the bases C D, Figures 1 and 2, which support the journals of a windlass, E, figs. 1 and 2, common with other arrangements generally used for that purpose.

Instead of the crank alone, a disk, F, figs. 1 and 2, is firmly keyed to the shaft, which is dished out, so that only a small portion of its surface touches the flat side of the ratchet-wheel G, Figures 1, 2, and 3.

The other face of the ratchet-wheel is provided with two circular wedges C C, which meet similar wedges c c, Figure 4, cast solid with the crank J, figs. 1, 2, and 4.

If, now, the crank is turned while the ratchet-wheel is stationary, it would, from the nature of the curves, slip on the shaft laterally, which is prevented by the nut N, fig. 2, screwed firmly against a shoulder on the shaft. When the crank has reached this nut N, the ratchet-wheel G is firmly wedged between the disk F, figs. 1 and 2, and the friction of the disk against the face of the ratchet-wheel will be sufficient to wind up the bucket full of water.

The pawl M, fig. 1, always in position, prevents the ratchet-wheel from going backward, and also the shaft, because a wire spring, S, fig. 1, has the tendency to press the shaft forward, and tighten the three parts together, as it is wound around the shaft,

and rests with one end on the heel of the cam C, with the other on the crank J, and is made to have sufficient strength, and cause so much pressure in these parts, as to stop the descent of a full bucket, at any place. Then a slight pressure backward on the crank, sufficient to counterbalance the spring S, is sufficient to diminish the friction of the disk against the ratchet-wheel, so that the weight of the bucket will cause its descent without any other motion of the crank.

In order to prevent the too sudden descent of the bucket, by the total absence of friction on the disk, the heels m n of the crank, fig. 4, have small lids cast, which serve as supports for some coil-springs which press against the corners of the ratchet-wheel, even when the pieces of the cams are out of contact, in securing at that time an easy descent of the bucket, entirely under the control of the operator.

A short flat chain, x x, fig. 1, is used on the end of the rope, and, in order to insure the proper winding up of the same on the windlass, a rod, v v, fig. 1, is worked in the frame A A, fig. 1, carrying a loose pulley, P, which serves as a guide, and conducts the rope always in such position as to bring the knobs on the bucket in contact with the dipping-rod of the concern.

I claim—

1. The crank J, having curved arms m and n, as described, in combination with ratchet-wheel G, disk F, and spring S, all arranged to operate substantially in the manner and for the purpose herein set forth.
2. The within-described arrangement of devices for elevating water, consisting of crank J, ratchet-wheel G, disk F, bases C D, spring S, shafts N O, spools E P, pawl M, and frame A, all operating in the manner described.

MATTHEW D. GRAY.
